(57) **CLAIM**

The ornamental design for a plate shape plant grow light as shown and described.

DESCRIPTION

FIG. 1 is a front, right and top perspective view of a plate shape plant grow light, showing my design.
FIG. 2 is a rear, right and bottom perspective view thereof.
FIG. 3 is a front elevation view thereof.
FIG. 4 is a rear elevation view thereof.
FIG. 5 is a left side elevation view thereof.
FIG. 6 is a right side elevation view thereof.
FIG. 7 is an enlarged top plan view thereof.
FIG. 8 is an enlarged bottom plan view thereof.
FIG. 9 is an enlarged view of detail 9 in FIG. 1.
FIG. 10 is an enlarged view of detail 10 in FIG. 1.
FIG. 11 is an enlarged view of detail 11 in FIG. 2.
FIG. 12 is an enlarged view of detail 12 in FIG. 2.
FIG. 13 is a front, right and top perspective view of a second embodiment of a plate shape plant grow light.
FIG. 14 is a rear, right and bottom perspective view of the second embodiment of the plate shape plant grow light of FIG. 13.
FIG. 15 is a front elevation view of the second embodiment of the plate shape plant grow light of FIG. 13.
FIG. 16 is a rear elevation view of the second embodiment of the plate shape plant grow light of FIG. 13.
FIG. 17 is a left side elevation view of the second embodiment of the plate shape plant grow light of FIG. 13.
FIG. 18 is a right side elevation view of the second embodiment of the plate shape plant grow light of FIG. 13.
FIG. 19 is an enlarged top plan elevation view of the second embodiment of the plate shape plant grow light of FIG. 13.
FIG. 20 is an enlarged bottom plan elevation view of the second embodiment of the plate shape plant grow light of FIG. 13.
FIG. 21 is an enlarged view of detail 21 in FIG. 13.
FIG. 22 is an enlarged view of detail 22 in FIG. 13.
FIG. 23 is an enlarged view of detail 23 in FIG. 14; and,
FIG. 24 is an enlarged view of detail 24 in FIG. 14.
The broken lines depict portions of the plate shape plant grow light that form no part of the claimed design. The dot-dash broken lines in FIGS. 1-2, 9-14, and 21-24 depict the boundaries of the enlargements that form no part of the claimed design.

1 Claim, 24 Drawing Sheets
